UNITED STATES PATENT OFFICE.

WYATT B. MADDEN, OF SALT LAKE CITY, UTAH.

MATCH-BOX.

1,198,042.

Specification of Letters Patent. Patented Sept. 12, 1916.

Application filed June 23, 1915. Serial No. 35,917.

To all whom it may concern:

Be it known that I, WYATT B. MADDEN, a citizen of the United States, residing at Salt Lake City, in the county of Salt Lake 5 and State of Utah, have invented new and useful Improvements in Match-Boxes, of which the following is a specification.

This invention relates to improvements in match boxes, the object of the invention being to provide an improved match box which is adapted to hold a quantity of matches and is provided with means for delivering the matches one at a time as needed.

15 The invention consists in the construction, combination and arrangement of devices hereinafter described and claimed.

In the accompanying drawings: Figure 1 is a vertical longitudinal sectional view of 20 a match box constructed in accordance with my invention. Fig. 2 is a transverse sectional view of the same. Fig. 3 is a detail view. Fig. 4 is a detail perspective view of the inner case. Fig. 5 is a similar view 25 of the ejector. Fig. 6 is a detail plan of the bottom of the outer case, showing the construction of the cam groove.

In the embodiment of my invention I provide an outer case 1 and an inner case 2.

30 The outer case has a bottom 3, a front wall 4, end walls 5, a hinged top 6 and is also provided with a pair of inner walls 7 which are spaced from the end walls 5 thereby forming a central vertical chamber 8 in 35 the outer case and chambers 9 and 10 at the ends of the outer case. The chamber 8 is open at its lower end, the bottom 11 of the chamber 9 is spaced from the bottom 3 of the outer case and the chamber 10 has an inclined bottom 12 which leads to a hinged door 13 in the contiguous end wall 5. The upper end of the chamber 8 is formed by a 40 horizontal partition 14 in which is a slot 15. A chamber 16 is thereby formed above the partition. The end wall 5 at a point below the chamber 9 is provided with a match delivery opening 17, the other end wall 5 is provided at its lower end with an opening 18.

45 The inner case 2 is detachably fitted in the chamber 8 with its upper open end under the partition 14. The inner case has its rear wall provided with an opening 19. The front and rear walls of the inner case are 50 inclined and converge downwardly at their lower ends as at 20 to form a contracted

passage 21 for the matches placed in said inner case. At one side at the lower end of the inner case are bearings 22 for a shaft 23. Said shaft has match fitting valves 24 secured thereto for rotation therewith. The said valves are provided with radially spaced arms 25 which are adapted to enter the passage 21 through openings or slots 26 in the lower portion of the rear wall of 60 the inner case. A follower 27 is provided to press downwardly on the matches in the inner case. This follower is arranged for vertical movement in the inner case and is connected pivotally as at 28 to the crossed arms 29 at the lower end of a lazy-tongs 30, the upper crossed arms 31 of the lazy-tongs extending through the slot 15 being pivotally connected together and to the partition 14 by a suitable pin 32 and having their 65 ends attached to a coiled retractile spring 33. It will be understood that the spring 70 coacts with the lazy-tongs to force the follower downwardly.

A pair of guiding and igniting jaws 34 80 are arranged just within the opening 17 and are provided with opposing friction-surfaces 35. An ejector 36 is slidably mounted on the bottom 3 of the outer case and has a stud 37 which operates in a cam 85 groove 38 in the bottom of the outer case, said cam groove having a straight arm 39 and a substantially semi-elliptical arm 40 the ends of which communicate with the ends of the straight arm. Spring switch 90 elements 39^a, 40^a are arranged near opposite ends of the cam groove and respectively close normally across the arms 39, 40. The ejector also has a wing 41 for operating the match delivery valves. A coiled extensible spring 42 is arranged with one end engaged in the ejector and the other end bearing against one of the walls 5 near the opening 18. An operating cord 43, which in practice may be a wire or a chain, passes 100 through the opening 15 and also through the spring 42 and is attached to the ejector. By the provision of the straight and semi-elliptical arms of the cam groove and the provision of the spring switch, the stud 37 105 of the ejector, when the ejector is moved in one direction will travel in the straight arm 39 thus keeping the wing 41 in a path which will cause the wing to engage an arm of one of the valves and thereby turn the 110 shaft 23 in one direction. On the reverse movement of the ejector, the spring switch

39^a will guide the stud 37 into the curved arm 40 and hence the ejector will be moved laterally and cause the wing 41 to clear the valve. Near the end of the reverse 5 movement of the ejector, its stud 37 passes again into the straight arm 39 of the cam slot, the spring switch 40^a keeping the switch in said slot and during the next ensuing movement of the ejector, the wing 41 10 will again coact with one of the valves to impart another partial rotation to the shaft 23 and said shaft will only be turned in the required direction to cause its valves to drop the matches singly and in succession from 15 the discharge passage of the inner casing. By drawing on the chain or cord the ejector 20 can be moved in one direction against the tension of the spring 42 and its wing caused to partly turn the valves so that the valves 25 can cause a match to drop from the bottom of the inner case to the bottom of the outer case directly in front of the ejector. When the cord is relaxed the spring 42 then moves the ejector in the reverse direction, 30 causing the ejector to force the match partially through the opening 17 and between the jaws 34. When the match is gripped and drawn out through the said opening, the head, which is at the lower end, in passing 35 between the jaws is ignited by the friction surfaces thereof. Burned matches may be placed in the chamber 10, the upper end of which is open. The door 13 enables the burned matches to be cleared out from said chamber when desired. The inner case is

held in the outer case by a detachable rear wall 44 with which the outer case is provided. Before supplying matches to the inner case the follower must be pressed upwardly, which may be readily done by engaging the follower with the thumb and the spring 33 with the fore or middle finger. 40

Having thus described my invention I claim:—

1. In a match box, a hopper element having a match discharge passage, revoluble valves to engage and force matches singly from said passage, a match ejector mounted for reciprocating movement and having means to actuate the valves, and means to 50 operate said ejector.

2. In a match box a hopper element having a match discharge passage, revoluble valves to engage and force matches singly from said passage, an outer case in which 55 said hopper element is arranged and having a bottom spaced from said discharge passage, a match ejector mounted for movement on the bottom of the outer case and having means to actuate the valves, a spring 60 to move the ejector in one direction and a cord to draw it in the reverse direction, against the tension of the spring.

In testimony whereof I affix my signature in presence of two witnesses.

WYATT B. MADDEN.
